UNITED STATES PATENT OFFICE.

BASIL F. SHAVER, OF EAST ST. LOUIS, ILLINOIS.

WIRE-ROPE FITTING.

1,314,542.

Specification of Letters Patent. Patented Sept. 2, 1919.

Application filed February 18, 1919. Serial No. 277,848.

To all whom it may concern:

Be it known that I, BASIL F. SHAVER, a citizen of the United States, residing at East St. Louis, in the county of St. Clair 5 and State of Illinois, have invented certain new and useful Improvements in Wire-Rope Fittings, of which the following is a specification.

The invention has relation to a novel form 10 of fitting to be secured to a wire rope, the purpose being to minimize the number of parts and to reduce the cost to the smallest amount possible consistent with efficiency and durability.

15 The drawing illustrates a preferred embodiment of the invention. However, it is to be understood that in adapting the same to meet different conditions, various changes in the form, proportion, and minor details 20 of construction may be resorted to without departing from the nature of the invention as claimed hereinafter.

Referring to the drawing hereto annexed, Figure 1 is a side view of a wire rope 25 fitting embodying the invention.

Fig. 2 is an edge view thereof.

Fig. 3 is a central longitudinal section, the dotted lines indicating the position of the wire rope.

30 Fig. 4 is a horizontal section on the line 4—4 of Fig. 1.

Corresponding and like parts are referred to in the following description and indicated in the several views of the drawing by like 35 reference characters.

The fitting comprises an engaging end of head 1 and a shank 2. The engaging end or head 1 may be of any form usually given to a fitting to be secured in the bight of a 40 wire rope. The engaging end or head 1 may have an opening 3 of any outline depending upon the specific purpose for which the fitting is designed, it being understood that wire rope fittings of the nature of the 45 present invention have their engaging ends provided with variously formed openings. A channel 4 is formed about the edge of the engaging end or head 1 and constitutes a seat to receive the wire rope which is indicated by the dotted lines 5 in the several 50 views.

The walls of the channel 4 are preferably smooth, as indicated most clearly in Figs. 2 and 3. The shank 2 has a waved outline

imparted thereto, the purpose being to deflect the portions of the wire rope clamped thereagainst so as to prevent slipping. The waved outline of the shank 2 is indicated most clearly in Figs. 1 and 3. A channel 6 is formed in opposite sides of the shank 2 60 to receive the wire rope. The walls of the channel 6 are serrated, the serrations having a spiral arrangement to conform to the strands of a wire rope so as to snugly receive the same and thereby assist materially 65 in securing the rope against possible displacement. The channel upon one side of the shank 2 is closed at its upper end, as indicated at 7 to form a stop for the extremity of the wire rope to butt against. 70 The channel upon the opposite side of the shank 2 is open to provide unobstructed passage for the wire rope.

A plurality of clips 8 coöperate with the shank 2 to secure the wire rope thereto. The 75 clips 8 are alternately disposed, this arrangement having been found to give the result in firmly securing the wire rope to the fitting. The clips 8 are supported in openings and in the preferable construction ap- 80 pertured ears 9 project from opposite edges of the shank 2 and have a staggered arrangement, as indicated most clearly in Fig. 1, the ears upon one side of the shank being disposed opposite the spaces between the 85 ears located upon the opposite side of the shank. The spaces between the ears 9 on one side of the shank provide clearance for the clips applied to the ears on the opposite side of the shank. That portion of the 90 shank lined between the ears on the same side is depressed, as indicated most clearly in Figs. 1 and 3 and the wire rope is drawn into the depressed portion by the clip. The 95 clips 8 are of usual formation and their members embrace the edges of the shank and pass through the openings of the ears 9 beyond which they project to receive the co-operating clamp nuts.

In the application of the invention the 100 wire rope 5 to be secured to the fitting is passed about the fitting and is seated in the channels 4 and 6 after which the clips 8 are placed in position alternately from opposite sides of the shank and are tightened 105 in a manner well understood.

The waved formation of the shank 2 in conjunction with the serrations in the walls

of the channel 6 insure a firm connection of the wire rope with the fitting after the clips 8 have been properly applied and tightened.

The foregoing description and the drawing have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A wire fitting of the character specified, comprising an engaging end and a shank, the latter having a waved outline in its length and clips alternately applied to opposite sides of the shank for clamping the rope against opposite sides thereof.

2. A rope fitting of the character speci-

fied, comprising an engaging end and a shank, the latter having a waved outline in its length, apertured projections at the sides 25 of the shank and clips supported in the apertured projections and alternately disposed on opposite sides of the shank to clamp the rope thereagainst.

3. A rope fitting, comprising an engaging 30 end and a shank, the latter being of waved outline in its length and the end and shank having a channel which forms a seat for the rope, the channel in the sides of the shank being serrated, apertured ears at the sides 35 of the shank and having a staggered arrangement and clips supported in the ears and applied to opposite sides of the shank.

In testimony whereof I affix my signature in presence of two witnesses.

BASIL F. SHAVER.
